CONVERTIBLE MAGNETO

Le Roy S. Dunham, East Orange, and Arthur F. Robertson, Belleville, N. J., assignors to Edison-Splitdorf Corporation, West Orange, N. J., a corporation of New Jersey

Application May 12, 1933, Serial No. 670,654

14 Claims. (Cl. 123—149)

This invention relates to a special design of electric generator of the magneto type, especially adapted for use in igniting charges in internal combustion engines.

- 5 It is the principal object of our invention to provide a magneto in which the main frame structure can be utilized in a considerable number of machines suitable for different ignition purposes.
- 10 It is another object of our invention to provide a single unitary frame structure which, while attaining the main object as expressed above, at the same time reduces the cost of manufacture, as the number of parts required
- 15 to build the various combinations, which will be hereinafter set forth, is reduced to a minimum. This improved design allows the main magneto structure to be convertible into any one of a number of different styles of magnetos suitable
- 20 for various purposes, from a one-cylinder engine to any of the usual number of multi-cylinder engines.

The various styles of magnetos which may be developed from the fundamental frame structure will be more specifically hereinafter set forth.

Our invention will be understood by reference to the annexed drawings, wherein:

Figure 1 is a longitudinal view through one style of magneto, a single-cylinder fixed spark machine being illustrated.

Figure 2 is a section on the line 2—2 of Figure 1, but with the ignition coil omitted, the condenser shown in dotted position, and the rotor at the point where the spark is produced, the direction of rotation being indicated by the arrow.

Figure 3 is a fragmentary plan-view of a portion of the upper part of the magneto frame structure with the removable top taken off.

Figure 4 is a cross-sectional view on the line 4—4 of Figure 5, but showing a higher top for the frame than that shown in Figure 1.

Figure 5 is a plan-view of the under side of either the low top shown in Figure 1, or the high top of Figure 4.

Figure 6 shows a sectional view on the line 6—6 of Figure 7, through the breaker end of the magneto of a two-cylinder manual advance type.

Figure 7 is a plan-view of Figure 6, showing the method of fastening the advance lever arm and the circuit breaker guide pin, and also showing the ends of the timer plates.

55 Figure 8 is a fragmentary side-view of part

of Figure 7, showing the advance lever and timer plates.

Figure 9 is a plan-view of the fixed timer plate.

Figure 10 is a plan-view of the movable timer plate which is associated with the plate shown in Figure 9.

Figure 11 is a vertical, sectional, elevational view on the line 11—11 of Figure 12, through a four-cylinder style of magneto using our unitary frame structure.

Figure 12 is an end-view of Figure 11.

Figure 13 shows a further modified form of magneto on the line 13—13 of Figure 14, showing a type of distributor such as used on battery installations.

Figure 14 is a part-sectional view and part-elevational view on the line 14—14 of Figure 13.

Referring now to the details, wherein like numbers refer to corresponding parts in the various views, 1 is a frame structure having a plurality of mounting bosses 2. The frame structure carries a core 3 for an ignition coil 4. The core 3 is made up in the usual manner of a plurality of laminations of good magnetic material. As shown in Figure 2, the lower end of the core is provided with horns or projections 5 which are interlocked in the die-casting process with the frame structure 1. By utilizing the construction as indicated, a very secure mounting for the core 3 is obtained whereby the machining operations across the top of the core will not loosen it or disturb its mounting in the frame.

The frame 1 also carries a group of laminations comprising a keeper 6, the upper end of which terminates in a line parallel with the free end of the core 3. The frame structure 1 also carries a pole-shoe 7 which preferably has a seat 8 for a magnet 9, the magnet being held in position in the frame by screw 10. The frame 1 has integral end members 11 and 12 between which is positioned a rotor shaft 13 preferably carried on anti-friction bearings 14 and 15. The shaft 13 carries an inductor 16 which serves to vary the flux through the core 3 and hence through the coil 4. Adjacent the coil 4 is a condenser 17 shown in dotted lines in Figures 1 and 2. The end-member 11 of the frame also carries an insulator 18 which supports a high-tension terminal 19, a cable 20 being indicated as running from the terminal 19 to the coil 4.

The unitary frame structure so far described, can be built up or converted into a number of

55

various types of magnetos which will now be described.

For certain types, the frame structure is provided with a top as shown in Figure 1, which 5 comprises a box-type frame 21 composed of non-magnetic material preferably similar to the frame 1, and in this box 21 there is mounted, as more particularly shown in Figure 5, a group of laminations 22 which comprises a yoke extending 10 across the outer ends of the core 3 and the keeper 6, and to a point where the ends thereof are engaged by the magnet at the point 23. The laminations 22 are riveted together by pins 15 24 which extend into the wedge-shaped pieces 25 and 26, and they may also extend, as shown in Figure 5, into the box-frame 21, thereby locking the laminations 22 securely in position in the top of the magneto. This top is held to the frame structure in any satisfactory manner 20 as by screws entering screw-holes, two of which are shown at 27 in Figure 3.

As shown in Figure 1, the end-member 12 is fitted with a breaker-box 28, being held thereto in any satisfactory manner as by a plurality of 25 screws 29. The breaker-box 28 carries a stud 30 on which is mounted the arm of a movable circuit breaker which is operated by a cam 31 fastened to the shaft 13 by a screw 32. The breaker-box 28 is provided with a cover 33 held 30 in position by springs 34. Thus is provided, as shown in Figure 1, a single cylinder fixed spark magneto, and in such type magneto it is sometimes desirable to use a grounding switch as indicated by the push-button 35 shown in dotted 35 line, which is adapted to engage contact spring 36 connected to a grounding stud 37 to which one end of the primary of the coil 4 is connected. While the condenser 17 is shown within the frame structure 1, it may in some cases be carried 40 in the combination bearing and circuit-breaker housing.

In Figure 4, the construction of the cover is similar to that just described with respect to 45 Figure 1, except that it is deeper, including of course the laminations 22. Using this deeper cover, provides a greater space for the coil 4 and a larger coil may be used, together with a longer magnet 9. These conversions produce a magneto like Figure 1, but having a greater output 50 which is sometimes desirable, depending on the size of the engine to which the magneto is applied.

Suppose now it is desired to have a variable spark with this single-cylinder magneto that 55 has been described in Figure 1. To obtain this, the style of bearing and breaker-box housing 28, shown in Figure 1, is removed, and a bearing and breaker-box housing 51, such as shown in Figures 6, 7, and 8, is put on in its place. In 60 this type of combination housing, there are two side-channels 38 and 39 in which is first mounted, by means of screw-holes 40, a timer plate 41 having its outer surface preferably provided with a plurality of longitudinal parallel serrations 42, and also having a slot 43. Mounted in 65 juxtaposition against the timer plate 41, is a cooperating timer plate 44 having the same serrations 42 as on the plate 41, and a slot 45 positioned over the slot 43. The timer plate 44 is 70 provided with a pair of end-slots 46 in which are positioned the screws 47 which pass through the slots 46 into the holes 40 in the frame of the magneto.

This construction just described gives an adjustment for the plate 44 whereby the position

of the slot 45 may be varied, and consequently the throw of the advance lever 48 is changed according to the position of the plate 44 with respect to the plate 41. This enables the circuit breaker to be properly timed with respect to the break of the inductor 16 from the pole-tip 49, whereby the spark will be produced at the proper time with respect to the maximum change of the flux through the coil-core 3. It may be mentioned that the advance lever 48 is fastened 10 to a cup-shaped breaker plate 50 which rotatably fits within the breaker-box 51, it being understood that the circuit breaker parts and cam are the same as have been described with respect to Figure 1. The lever 48 may be mounted 15 on either side of the circuit breaker housing, and when mounted, as for example in Figure 7, the slot in the breaker housing on the opposite side is covered by a plain plate 72. The bosses 2 have been provided to give a standard S. A. E. 20 height for the shaft 13, but if a shorter dimension is required between the mounting plate and the shaft center, the bosses 2 may be machined down to give the desired height.

Suppose now it is desired to have a two-cylinder magneto with a fixed spark, with a relatively low output. We would then use the frame structure and top of Figure 1 with the breaker-box 28, but the cover 33 is removed and a distributor cap 52, of good insulating material, 30 such as shown in Figures 6 and 7, is mounted in its place, being held in position by the same springs 34. It will be noted from Figure 6, that for a two-cylinder magneto, a different cam must be used, and this cam is slotted at 53 to 35 receive a distributing finger 54. The finger 54 carries a flexible contact spring 55 adapted to make contact with the terminal 56. The distributing finger 54 also carries a distributor contact member 57 which will distribute the sparks 40 to the terminals 58 and 59 in the usual manner for a jump spark machine. It is to be understood that the high-tension terminal 19 (see Figure 1) is connected by a flexible cable around the side of the magneto to the terminal 56, whereby 45 the sparking current is then distributed as has been described.

If a larger output is desired for this style of machine, the top 21 may be changed for the higher top as shown in Figure 4, with all of the 50 attendant advantages as have been described. If it is desired to convert or to have a two-cylinder variable spark machine, then the type of breaker-box 51 as shown in Figures 6, 7, and 8, is utilized in the same manner as has been 55 described for the single-cylinder magneto.

From what has been said, it will be seen that we can obtain, from the structures so far described, eight combinations, all utilizing the same frame structure including the same rotor.

If a four-cylinder magneto is desired, as illustrated in Figures 11 and 12, an additional housing member 60 is required for supporting a distributor gear 61 which is driven by a pinion 62 carried on the rotor shaft 13. The distributor gear 61 is supported on a bearing collar or member 63, on the outer end of which is a fitting 64 formed to carry the same distributor finger 54 as shown in Figure 6. The frame member 60 also carries a four-cylinder distributor block 65 and a circuit breaker which may be similar to that shown in the previous figures. However, the circuit breaker that is shown is that described in our Patent 1,887,624, issued 75

November 15, 1932. Therefore, the various parts need not be specifically described herein.

In this type of magneto, the frame structure remains the same and may use either the high 5 or the low top with the corresponding magnet as has been described, but the rotor shaft is somewhat longer in order to carry the pinion 62 and the circuit breaker parts. It may also be mentioned that the terminal 19 (see Figure 1) is 10 connected to the central terminal 66 by a flexible cable in the same manner as has been described with respect to the connection to the terminal 56 of Figure 6.

In Figures 13 and 14, we have shown a distributor, generally referred to by the number 15 67, of the battery ignition type, the drive for the distributor shaft 68 being made through a gear 69 and pinion 70 carried on the end of the rotor shaft 13. In this arrangement, the 20 rotor shaft 13, at the gear end 70, is of a different length than that shown in Figure 11, but in all forms of the magneto, the drive-end of the rotor shaft is the same standard S. A. E. type. It is also to be noted that in the form 25 shown in Figures 13 and 14, the same distributor finger 54 is utilized as in all the previous forms, and likewise, the same cup-shaped breaker-plate 50, as shown in Figure 6.

In this form, the cable from the high-tension 30 lead 19 is connected to the central terminal 71 in a similar manner as has been described with respect to the other forms. In this type of magneto, the high or low top for the frame structure may be utilized, thus giving, as so far 35 described, two types of magnetos of the form shown in Figures 11 and 12, and two types of the form shown in Figures 13 and 14.

A similar construction is followed out for six 40 or eight-cylinder machines as has been described with respect to the four-cylinder arrangements.

From what has been said, it will be understood that many of the details utilized in this 45 convertible magneto structure may be varied over a considerable range, without departing from the spirit of our invention and the scope of the appended claims.

Having thus described our invention, what we claim is:

50 1. In a convertible magneto having a rotor, the combination with a unitary frame structure, including a housing for the rotor and its field poles and an ignition coil with its associated core and field pole faces, said housing also directly carrying at the drive end, one of the rotor bearings; of a removable housing 28 at the breaker end, a rotor bearing and a circuit breaker carried by said housing, a cover for the housing and a removable top for the frame 55 structure, said top carrying core parts to complete the magnetic circuits of the coil-core, and a magnet extending from the rotor pole in the frame structure, into engagement with the core parts in said top.

65 2. In a magneto as set forth in claim 1, further characterized in that the characteristics of the magneto may be quickly changed by merely removing said top and replacing it with another having a different height, and replacing the magnet with one suited to said new top.

70 3. In a magneto as set forth in claim 1, further characterized in that the characteristics of the magneto may be quickly changed from a single-spark fixed ignition to a single-spark adjustable ignition by changing said housing to one

having a timing lever attached to the breaker plate in the housing and extending without the housing, said parts being quickly changeable for the reverse condition.

4. In a magneto as set forth in claim 1, further characterized in that the characteristics of the magneto may be quickly changed from a single-spark fixed ignition to a single-spark adjustable ignition by changing said housing to one having a timing lever attached to the breaker plate in the housing and extending without the housing, said parts being quickly changeable for the reverse condition, and further characterized in that the output characteristics of the magneto may be quickly changed by merely removing said top and replacing it with another having a different height, and replacing the magnet with one suited to said new top.

5. In a magneto as set forth in claim 1, further characterized in that the characteristics of the magneto may be quickly changed from a single-spark fixed ignition to a two-spark fixed ignition by changing the circuit-breaker cam, mounting a distributor finger thereon, changing said cover to a two-spark distributor block and connecting the secondary terminal of the coil to said block, said parts being quickly changeable for the reverse condition.

6. In a magneto as set forth in claim 1, further characterized in that the characteristics of the magneto may be quickly changed from a single-spark fixed ignition to a two-spark fixed ignition by changing the circuit-breaker cam, mounting a distributor finger thereon, changing said cover to a two-spark distributor block and connecting the secondary terminal of the coil to said block, said parts being quickly changeable for the reverse condition, and further characterized in that the output characteristics of the magneto may be quickly changed by merely removing said top and replacing it with another having a different height, and replacing the magnet with one suited to said new top.

7. In a magneto as set forth in claim 1, further characterized in that the characteristics of the magneto may be quickly changed from a two-spark fixed ignition magneto to a two-spark variable ignition by substituting for the housing 28, the housing 51 and adjustable circuit breaker plate 50 with its associated parts, the remaining parts being those used in the two-spark fixed ignition magneto, said housing 51 and plate 50 being quickly changeable for the reverse condition.

8. In a magneto as set forth in claim 1, further characterized in that the characteristics of the magneto may be quickly changed from a two-spark fixed ignition magneto to a two-spark variable ignition by substituting for the housing 28, the housing 51 and adjustable circuit breaker plate 50 with its associated parts, the remaining parts being those used in the two-spark fixed ignition magneto, said housing 51 and plate 50 being quickly changeable for the reverse condition, and further characterized in that the output characteristics of the magneto may be quickly changed by merely removing said top and replacing it with another having a different height, and replacing the magnet with one suited to said new top.

9. In a magneto as set forth in claim 1, further characterized in that the characteristics of the magneto may be readily made into a multi-cylinder machine by applying to the frame structure, an additional housing carrying all breaker

and distributor parts for the desired number of cylinders, the rotor having a longer shaft as described.

10. In a magneto as set forth in claim 1, further characterized in that the characteristics of the magneto may be readily made into a multi-cylinder machine by applying to the frame structure, an additional housing carrying all breaker and distributor parts for the desired 10 number of cylinders, the rotor having a longer shaft as described, and further characterized in that the output characteristics of the magneto may be quickly changed by merely removing said top and replacing it with another having a different height, and replacing the magnet with one suited to said new top.

11. In a magneto as set forth in claim 1, further characterized in that the characteristics of the magneto may be readily made into a multi-cylinder machine by applying to the frame structure, an additional housing carrying all breaker and distributor parts for the desired number of cylinders, the rotor having a longer shaft as described, and further characterized in that the 25 output characteristics of the magneto may be quickly changed by merely removing said top and replacing it with another having a different height, and replacing the magnet with one suited to said new top, and still further characterized 30 in that the output characteristics may be still further changed by changing the ignition coil.

12. A convertible magneto comprising a unitary frame structure including a housing carrying; a rotor, field core parts and an ignition coil fitting around but easily removable from

one of said core parts when the top of the magneto is removed, a top for said frame structure quickly removable therefrom for substitution of another, and all carrying core parts to complete the magnetic circuits through the magneto, a magnet mounted for quick removal for substitution by another, and all extending from a rotor core part in the frame structure to the core part in the top as selected, and a removable bearing and circuit breaker housing fitting said 10 frame structure for quick removal therefrom for substitution of another as and for the purposes described.

13. A convertible magneto as set forth in claim 12, characterized in that the same frame 15 structure may be utilized and quickly converted by fitting it with one of different tops, magnets, coils, circuit breakers and distributors to suit the ignition requirements.

14. An adjustable spark magneto having a circuit breaker housing for enclosing the breaker parts, said housing having oppositely disposed side channels, a fixed plate and an adjustable plate fitting in at least one of said channels, said plates having their engaging surfaces ser- 20 rated, and said adjustable plate having end-slots 25 whereby the plate may be accurately and permanently positioned on the fixed plate to properly time the rotor field break and the circuit breaker, both plates having cooperating lever 30 slots and a timing lever passing through said slots into engagement with a part of the circuit breaker.

LE ROY S. DUNHAM.

ARTHUR F. ROBERTSON.
